United States Patent Office

Des. 223,636
Patented May 16, 1972

223,636

CALIBRATED COMPASS

Richard O. Finley, 2608 Graham Ave., Apt. C,
Redondo Beach, Calif. 90278

Filed Feb. 4, 1971, Ser. No. 112,849

Term of patent 14 years

Int. Cl. D10—04; D19—06

U.S. Cl. D52—6

FIG. 1 is a perspective view of a calibrated compass showing my new design;

FIG. 2 is a rear elevational view thereof;

FIG. 3 is a right end elevational view thereof;

FIG. 4 is a top plan view of FIG. 2;

FIG. 5 is a bottom plan view of FIG. 2.

I claim:

The ornamental design for a calibrated compass, as shown.
